EDWARD A. ESCHINGER, OF PHILADELPHIA, PENNSYLVANIA, ASSIGNOR OF ONE-HALF
TO JOEL G. CLEMMER, OF PHILADELPHIA, PENNSYLVANIA.

TALKING-MACHINE.

1,301,786.

Specification of Letters Patent. Patented Apr. 22, 1919.

Application filed March 20, 1918. Serial No. 223,525.

To all whom it may concern:

Be it known that I, EDWARD A. ESCHINGER, a citizen of the United States, residing at Philadelphia, in the State of Pennsylvania, 5 have invented a certain new and useful Improvement in Talking-Machines, whereof the following is a specification, reference being had to the accompanying drawings.

My invention relates to sound recording 10 and reproducing machines, including gramophones and graphophones; and particularly feed mechanism for sound boxes of such machines adjustable to automatically repeat their coöperation with a given sound record, at the will of the operator.

As hereinafter described, my invention is specifically adapted for such machines arranged to coöperate with flat disk records, and having sound conducting tubular arms, 20 or horns which move with the sound boxes, and are so constructed and arranged that repetition of the coöperation of the sound box with any given record is consequent upon such movement, to an adjustably predetermined extent.

I find it convenient to illustrate and describe my invention herein in connection with a gramophone of the type known commercially as a "Victor talking machine". 30 However, it is to be understood that I do not desire to limit myself to such a specific embodiment of my invention, which includes the various novel features of construction and arrangement hereinafter more definitely specified.

The two embodiments of my invention chosen for illustration herein, though specifically different in their details of construction, each include means to variably 40 predetermine the initial and terminal positions of respective sound boxes with reference to given sound records, in combination with a single rotary cam constructed and arranged to automatically lift the sound box 45 from coöperative relation with the record when it reaches a variably predetermined terminal position, and to then return the sound box to its initial position and again lower it into coöperative relation with the 50 record; said cam having the capacity to shift said sound box throughout the maximum range of its movement by frictional engagement of a cam plate carried with the sound box; but its effective capacity is adjustably variable in accordance with varia-

tions in the extent of different sound records.

Therefore, it is to be noted that the specific forms of feed mechanism herein disclosed are covered by the generic claims in 60 my copending application Serial 175,082, filed June 16, 1917, for Letters Patent of the United States, in which the specific claims are limited to construction and arrangement differing from the disclosures herein. It 65 may be observed that the embodiments of my invention herein claimed are distinguished from those in my copending application aforesaid in that the adjustable terminal stop devices are carried by the tone 70 arms, instead of being mounted upon the machine frame or casing.

In the drawings; Figure I is a plan view of the Victor gramophone aforesaid, having a convenient embodiment of my invention 75 in connection therewith.

Fig. II is a fragmentary vertical sectional view of the machine shown in Fig. I.

Fig. III is a fragmentary plan view of the feed mechanism shown in Figs. I and II, 80 but on a larger scale.

Fig. IV is a left hand side elevation of a portion of the said feed mechanism, as shown in Fig. III; said mechanism being in idle position, disconnected from the motor which drives it.

Fig. V is a fragmentary, sectional, front elevation of a portion of the feed mechanism shown in Figs. I to IV inclusive.

Fig. VI is a fragmentary plan view, similar to Fig. III, but showing the said mechanism in operative position, in connection with the motor which drives it.

Fig. VII is a fragmentary, vertical, sectional view of the feed mechanism terminal 95 stop device, taken on the line VII in Fig. III.

Fig. VIII is a plan view of a modified form of initial stop device.

Fig. IX is a fragmentary elevation of the 100 initial stop device shown in Fig. VIII.

Fig. X is a plan view of a modified form of an initial stop device.

Fig. XI is a front elevation, and Fig. XII is a side elevation, of a modified form of initial stop device, of the same general character as the terminal stop device shown in Fig. III and which may be substituted for the initial stop device shown in that figure.

Fig. XIII is a fragmentary perspective 110

view of the bracket attached to the tone arm, affording a support for the fulcrum of the feed mechanism lever, and a support for the sound box when the latter is upturned 5 into idle position.

Fig. XIV is a side elevation, similar to Fig. IV, but showing a more compact arrangement of the cam and gear shifting mechanism, designed for the smaller type 10 No. IX Victor machine, but adapted for use in the larger, No. XVI, machine indicated in Figs. I and II.

Referring to the form of my invention shown in Figs. I to VII inclusive; as shown 15 in Figs. I and II, the casing 1 incloses a gramophone including the record turn table 2 arranged to be turned by the motor 3 which is mounted upon the under side of the casing top 4 which is detachably rigidly secured in said casing 1. The sound box 5 includes a vibratory diaphragm, and carries the stylus 6, arranged to traverse a groove in the record 8 on said turn table 2 and automatically shift said box toward the axis 20 of said table. Said sound box 5 is attached to the tubular goose neck 10 mounted to turn upon the axis 11 in the cross tube 12 in the tubular tone arm 13 which thus carries said sound box 5. Said tone arm 13 is mounted 25 to swing, in a horizontal plane, upon its vertical pivot pin 14 which is journaled in the bearing 15, rigidly connected with said casing top 4, at the upper end of the amplifying horn 16, which is stationary in said 30 casing 1; as indicated in Fig. II.

Said goose neck 10 carries the lever 17, extending beneath said tone arm 13 as shown in Fig. II, whereby said sound box 5 and stylus 6 may be raised from and returned to 40 the operative position shown in Figs. I and II. Such movement is automatically effected by the lever 18 which is fulcrumed at 19 in the bracket 20 which is detachably rigidly connected with said tone arm 13. Said lever 18 has the arcual arm cam plate 45 22 which registers with the cam 24, which has the capacity to shift said sound box 5 throughout the maximum range of its movement, away from the axis of said turntable 50 2, by frictional engagement with said arcual arm.

As shown in detail in Figs. III to VI inclusive; said cam 24 is rigidly connected with the shaft 26 which is mounted to reciprocate in the frame 27 which is rigidly connected with said casing top 4. Said shaft 26 also has rigidly connected therewith the gear 28 whereby said shaft 26 and cam 24 are turned, when said gear is engaged with the 60 driving gear 30 upon the vertical driving shaft 31, which, as shown in Fig. II, is journaled in said frame 27 and in the frame 32 and carries, near its lower end, the gear 34 engaging the gear 35 on the shaft 36 carrying the gear 37 engaging the gear 38 on the shaft 65

39 having the gear 40 engaging the gear 42 of said motor 3; so that said motor, which rotates the turn table 2, also operates my improved feed mechanism.

Said gear 28, of the feed mechanism, is 70 automatically shifted both to and from engagement with said gear 30 by the single spring 45, co-operating with the mechanism shown in detail in Figs. III to VI inclusive. Said spring 45 is attached at one end to the 75 tappet 47, by the screw 48 which secures said tappet upon the slide bar 49, which is mounted to reciprocate in said frame 27. The opposite end of said spring 45 is attached to the lever 51 which is fulcrumed at 52 upon said frame 27 and has the stud 54 at its opposite end engaging the annular groove 55 in the sleeve 56 which is rigidly secured to said shaft 26 by the screw 57. Said slide bar 49 registers with the crown cam 59, carried by said gear 28 on the shaft 26; so that rotation of said gear 28, in the direction of the arrow marked thereon in Fig. III, thrusts said slide bar 49 into the position shown in Figs. III and IV, 80 in which said spring 45 is stretched, and, by its tension shifts said rigidly connected cam 24, shaft 26, and gear 28, to the idle position shown in Figs. I to V inclusive. Said slide bar 49 is detained in that position 85 by the tripping lever 54, which is fulcrumed at 55 on said frame 27 and has its hooked end engaging said tappet 47, as shown in Fig. III, under pressure of the spring 58 which is carried by said lever 54 and bears 90 upon said tappet 47. In such idle position of the feed mechanism, the stud 60 on said frame 27 extends in the notch 61 in said sleeve 56, as shown in Fig. IV; thus insuring 95 that said cam 24 shall be in the rotary position shown in Fig. V, when the gear 28 is disengaged from the gear 30 by the action of said spring 45, and further insuring that it shall not be accidentally turned while said gears are thus disengaged.

Said spring 45 operates to shift the clutch gear 28 in both directions, solely by tension of said spring, and in both instances effects a change in the angular relation of the lever 51 with reference to the plane which is common to the axes of said shaft 26 and said slide bar 49. When said spring 45 has its end which is attached to the tappet block 47 held stationary, by engagement of said block with the detent 54, as shown in Fig. III; 105 said spring tends to increase the angle between the upper edge of said lever 51 and said plane, thus tending to shift said shaft 26 and its appurtenances away from the driving gear 30. However, when that end of said spring 45 is free to move, by release of said detent 54 from said tappet 47, as indicated in Fig. VI, said spring tends to decrease the angle aforesaid, by drawing said tappet block 47 and said lever 51 closer to- 110 115 120 125 130

gether and, because said lever 51 is anchored to the frame 27 at its fulcrum 52, the tension of said spring then effects movement of said shaft 26 and its gear 28 toward said gear 30, 5 to engage said gears.

It may be observed, that in said idle position of the gear shifting mechanism above described, the slide bar 49 has been released by the cam 59 which stretched said spring 10 45 to effect the disengagement of said gear 28 from the gear 30, and that said spring 45 is therefore free to contract and shift said cam 24, shaft 26, and gear 28 in the opposite direction, when said tappet 47 is released by the detent lever 54. Such release is conveniently effected by providing said lever 54 with the upturned arm 63 in position to encounter a stop member carried by said tone arm 13. As it is the purpose 15 20 25 of my invention to shift said sound box from its terminal position upon any record, to its proper initial position with respect to such record; it is important to note that there is considerable variation in the radial position 30 35 40 45 of the initial and terminal portions of sound record grooves in records of the same nominal size and, therefore, I provide stop mechanism which is adjustably variable to predetermine the initial and terminal positions 50 55 60 65 70 75 80 85 90 95 100 105 110 115 120 125 of said sound box 5 with reference to any given record. For instance, the adjustable stop member 64 shown in Figs. III and V is a gear rack carried by said lever 18; said rack being mounted to reciprocate, horizontally, in the slide bearing 65 on the dial plate 67 which is conveniently riveted to the arm 22 of said lever 18 as indicated at 68 in Figs. III and V. As shown in Figs. III, V, and VII; said adjustable stop member 64 is engaged by the gear 70 which is rotatable by the knob 71 carrying the index pointer 72 which traverses the graduations 73 on said dial plate 67. Accidental displacement of said stop member 64 is prevented by the spring 75 carried by the shaft 76 of said gear 70 and frictionally engaging the back of said plate 67.

In the form of my invention shown in Figs. I and III, the initial stop device includes the base plate 79 which is rigidly connected with the casing top 4, by screws 80, and has the arcual slide plate 81 longitudinally adjustable thereon, said plate 81 having a pair of flanges 82 embracing said base plate 79, and having a slot 83 through which the clamp screw 84 extends in engagement with said base plate 79. When said screw 84 is loosened, by manually turning its milled head 85, said plate 81 may be longitudinally adjusted by its handle 86 to present its rubber covered end 87 in position to encounter the pendent arm 88 of said bracket 20 and thus predetermine the initial position 60 65 70 75 80 85 90 95 100 105 110 115 120 125 of the sound box 5, with reference to any given record 8, carried by said turn table 2.

The form of my invention above described operates as follows:

Any desired sound record, such as 8, being placed on the turn table 2; the tone arm 13 is turned until the stylus 6 registers with the initial end of the sound record groove indicated at 89 in Fig. I. Thereupon, said initial stop mechanism member 81 is adjusted to contact with said arm 88 carried by the tone arm 13 and thus insure that when the latter is returned, it will be stopped in the correct initial position with respect to that record. Said sound box 5 is then shifted toward the axis of the turn table 2 until the stylus 6 registers with the terminal convolution 9 of the sound groove in said record, and the terminal stop mechanism member 64 is then adjusted, by rotation of the milled head 71, until the tripping lever 54 is released from the tappet 47. Thereupon, said sound box 5 is automatically returned to the aforesaid initial position, by the operation of the feed mechanism above contemplated. That is to say; when said detent lever 54 is thus released, said spring 45 contracts and shifts the shaft 26 until the gear 28 thereon engages the driving gear 30, as shown in Fig. VI, thus withdrawing the sleeve 56 from its engagement with the stud 60 and permitting said cam shaft 26 to be rotated by the motor 3. Said cam 24 is thus turned in the direction of the arrow marked thereon in Fig. V, thus raising the arcual end of said lever 18 and correspondingly depressing its opposite end in engagement with the lever 17 carried by the sound box 5, and thus lifting the latter and the stylus 6 from coöperative relation with said record. The continued turning movement of said cam 24, in frictional engagement with said arcual end 22 of said lever 18, turns the tone arm 13 outward until said arm 88 pendent therefrom encounters the padded end 87 of the initial stop mechanism. Further turning movement of said cam 24 merely permits the arcual end of said lever 18 to be lowered by the weight of the sound box 5 until the stylus 6 assumes its initial position in coöperative relation with the record. During the last quarter revolution of said cam 24, the crown cam 59 thrusts the slide bar 49 to restore the spring 45 to its stretched position shown in Figs. III and IV, but said spring is not effective to release the gear 28 from the gear 30 until the notch 61 in the sleeve 56 is presented in registry with the stud 60 on the frame 27, as shown in Figs. III and IV.

Only a few seconds' intermission is required for the automatic return of the sound box from its terminal to its initial position as above contemplated, and the playing operation may be automatically repeated until the mechanism is stopped by the operator. As shown in Fig. XIII, I prefer to provide

said tone arm bracket 20 with the projection 21 upon which said sound box 5 may be rested in idle position; thus permitting noiseless operation of the feed mechanism, 5 and facilitating its adjustment.

The initial stop mechanism shown in Figs. I and III has the slot 83 in the slide bar 84 of such length as to permit the adjustment of the mechanism to play records of all of 10 the different diameters found in commerce. An initial stop device, having the same capacity but more compactly arranged, is shown in Figs. VIII and IX, wherein 90 is a base plate fixed upon the casing top 4 by 15 screws 91 and having the arcual slot 92 for engagement with the studs 93 and 94 which are fixed in the stop slide bar 96. Said stud 94 extends above said stop bar 96 to form the handle 97 by which said bar may be adjusted, and the spring 98, which is compressed between the head of said stud 94 and the under surface of said base plate 90 frictionally engages them so as to prevent accidental displacement of said bar. Said bar is 20 provided with the index pointer 100 whereby it may be precisely set with reference to the 25 graduations 101.

Of course, if the machine is to be restricted to the operation of records of a less 30 number of sizes than above contemplated; the range of adjustment of the initial stop mechanism may be correspondingly diminished. For instance, in Fig. X, I show an initial stop mechanism including the base 35 plate 102 fixed on the casing top 4 by the screws 103 and having the pairs of flanges 104 between which the stop slide bar 105 is adapted to reciprocate. Said stop bar has the slot 106 through which the screw stud 40 108 extends from said base plate 102, in engagement with the milled nut 109 by which said stop member 105 may be secured in adjusted position. Said stop member 105 is conveniently provided with the gear rack 45 110, engaged by the gear sector 111 which is fulcrumed upon the stud 112 and has the index pointer 113, provided with the handle 114 by which it may be precisely adjusted with reference to the graduations 115 on the 50 scale plate 116.

In Figs. XI and XII, I show an initial stop mechanism including elements similar to the elements of the terminal stop mechanism shown in Figs. III and V and including 55 the dial base plate 118, which is rigidly secured upon the casing top 4, by screws 119, in such position that its stop member 120 may encounter said arm 88 pendent from the bracket 20 on the tone arm 13. Said stop 60 member 120 is a gear rack slide bar mounted to reciprocate in the bearing 121 on the back of said base plate 118 and engaged by the gear 123 carried by the shaft 124 having the milled knob 125 carrying the index pointer 65 126 adapted to traverse the circular series of

graduations 127 on said plate 118. Accidental movement of said stop member 120 is prevented by the spring 128 compressed between said plate 118 and gear 123 and frictionally engaging them.

The gramophone indicated in Figs. I and III is of the large type mounted in a casing which rests upon the floor. I have found it desirable to more compactly arrange the gear shifting mechanism for machines of 70 the smaller type, and show in Fig. XIV such a modification of my invention, which was designed for use in the Victor No. IX machine, in which the casing is smaller than the casing 1 above contemplated and adapted to rest upon a table or other similar support. In said figure; the frame 130 has its base flange 131 resting upon the casing top 4 and its opposite end supported by the bearing 15 at the upper end of the amplifying horn 16, indicated in Fig. II. The cam shaft 133 is mounted to reciprocate in said frame 130, and carries the cam 134 adjoining the sleeve 135 whereby said shaft may be shifted, by mechanism constructed and arranged as above described, including a spring 45. This form of my invention may not only be set closer to the axis of rotation of the tone arm 13, but is of less extent with reference to the axis of the cam shaft than the form of my 80 invention shown in Figs. I to VI inclusive and is thus adapted for a machine of smaller dimensions than is shown in Figs. I and II.

Moreover, the stud 137 on said frame 130 is adapted to directly engage the notch 138 in said cam 134 when the gear 28 is shifted to idle position, as shown in Fig. XIV, and thus prevent accidental displacement of said cam until said gear is reengaged with the 90 gear 30.

It is to be understood that such an embodiment of my invention as indicated in Fig. XIV may be substituted for the larger gear shifting mechanism shown in Figs. I to VI inclusive, to coöperate with the lever 18 100 and other elements shown in the latter figures.

I do not desire to limit myself to the precise details of construction and arrangement of my invention herein set forth as it 115 is obvious that various modifications may be made therein without departing from the essential features thereof as defined in the appended claims.

I claim:

1. In a sound reproducing machine; the combination with a casing; of a motor arranged to turn a sound record table on said casing; an arm carrying a sound box arranged to coöperate with a sound record on 120 said table; an initial stop device, including a base fixed with respect to said casing, and a slide bar on said base, limiting the initial position of said arm at the outer limit of its movement with respect to the axis of said 125 130

- table; a terminal stop device, including a gear and gear rack slide bar, both journaled on said arm and limiting the terminal position of said arm at the inner limit of its movement toward the axis of said table; means arranged to raise said box and arm from said terminal position, shift them away from the axis of said table, and lower them to their initial position, including a cam revoluble on a horizontal axis; driving mechanism for said cam; gearing arranged to connect said motor and driving mechanism; a lever detent for said driving mechanism, fulcrumed on said casing, normally preventing rotation of said cam, but arranged to be encountered by said gear rack bar, whereby movement of the latter, caused by movement of said arm toward its terminal position, releases said detent and permits said driving mechanism to operate to return said arm and box to their initial position.
2. In a sound reproducing machine; the combination with a casing; of a motor arranged to turn a sound record table on said casing; an arm carrying a sound box arranged to coöperate with a sound record on said table; a terminal stop device, including a gear and gear rack slide bar, both journaled on said arm and limiting the terminal position of said arm at the inner limit of its movement toward the axis of said table; means arranged to raise said box from said terminal position, shift it away from the axis of said table, and lower it to its initial position, including a cam revoluble on a horizontal axis; driving mechanism for said cam; gearing arranged to connect said motor and driving mechanism; a detent for said driving mechanism, normally preventing rotation of said cam, but arranged to be operated by said terminal stop device, whereby movement of the latter, caused by movement of said box toward its terminal position, releases said detent and permits said driving mechanism to operate to return said box to its initial position.
3. In a sound reproducing machine; the combination with a motor arranged to turn a sound record table; of an arm carrying a sound box arranged to coöperate with a sound record on said table; an initial stop device, limiting the initial position of said arm at the outer limit of its movement with respect to the axis of said table; a terminal stop device, carried with said box, including a slide bar, limiting the terminal position of said box at the inner limit of its movement toward the axis of said table; means arranged to raise said box from said terminal position, shift it away from the axis of said table, and lower it to its initial position, including a cam revoluble on a horizontal axis; driving mechanism for said cam; gearing arranged to connect said motor and driv-
- ing mechanism; a detent for said driving mechanism, normally preventing rotation of said cam, but arranged to be encountered by said slide bar, whereby movement of the latter, caused by movement of said box toward its terminal position, releases said detent and permits said driving mechanism to operate to return said box to their initial position.
4. In a sound reproducing machine; the combination with a motor arranged to turn a sound record table; of an arm carrying a sound box arranged to coöperate with a sound record on said table; an initial stop device, limiting the initial position of said arm at the outer limit of its movement with respect to the axis of said table; a terminal stop device, including a nonadjustable member, supported independently of said box, and an adjustable member carried with said box, limiting the terminal position of said box at the inner limit of its movement toward the axis of said table; means arranged to raise said box from said terminal position, shift it away from the axis of the table, and lower it to its initial position, including a cam revoluble on a horizontal axis; driving mechanism for said cam; gearing arranged to connect said motor and driving mechanism; a detent for said driving mechanism, normally preventing rotation of said cam, but arranged to be operated by said terminal stop device, whereby movement of the latter, caused by movement of said box toward its terminal position, releases said detent and permits said driving mechanism to operate to return said box to its initial position.
5. In a sound reproducing machine; the combination with a motor arranged to turn a sound record table; of an arm carrying a sound box arranged to coöperate with a sound record on said table; a terminal stop device, including a nonadjustable member, supported independently of said box, and an adjustable member carried with said box, limiting the terminal position of said box at the inner limit of its movement toward the axis of said table; means arranged to raise said box from said terminal position, shift it away from the axis of the table, and lower it to its initial position, including a cam revoluble on a horizontal axis; driving mechanism for said cam; gearing arranged to connect said motor and driving mechanism; a detent for said driving mechanism, normally preventing rotation of said cam, but arranged to be operated by said terminal stop device, whereby movement of the latter, caused by movement of said box toward its terminal position, releases said detent and permits said driving mechanism to operate to return said box to its initial position.
6. In a sound reproducing machine; the combination with a motor arranged to turn a sound record table; of an arm carrying a sound box arranged to coöperate with a sound record on said table; an initial stop device, limiting the initial position of said arm at the outer limit of its movement with respect to the axis of said table; a terminal stop device, carried with said box, including a slide bar, limiting the terminal position of said box at the inner limit of its movement toward the axis of said table; means arranged to raise said box from said terminal position, shift it away from the axis of said table, and lower it to its initial position, including a cam revoluble on a horizontal axis; driving mechanism for said cam; gearing arranged to connect said motor and driv-

- a sound record table; of an arm carrying a sound box arranged to coöperate with a sound record on said table; an initial stop device, limiting the initial position of said 5 arm at the outer limit of its movement with respect to the axis of said table; a terminal stop device, including a nonadjustable member, supported independently of said box, and an adjustable member carried with said 10 box, limiting the terminal position of said box at the inner limit of its movement toward the axis of said table; means arranged to raise said box from said terminal position, shift it away from the axis of said table, and 15 lower it to its initial position, including a cam; driving mechanism for said cam; and means controlled by said terminal stop mechanism, whereby movement of said box toward its terminal position, causes said 20 driving mechanism to operate to return said box to its initial position.
7. In a sound reproducing machine; the combination with a motor arranged to turn a sound record table; of an arm carrying 25 a sound box arranged to coöperate with a sound record on said table; an initial stop device, on said casing, limiting the initial position of said arm at the outer limit of its movement with respect to the axis of said 30 table; a terminal stop device limiting the terminal position of said arm at the inner limit of its movement toward the axis of said table; means arranged to raise said box from said terminal position, shift it away 35 from the axis of the table, and lower it to its initial position, including a cam; driving mechanism for said cam; a bearing bracket on said arm arranged to coöperate with said initial stop device; a lever fulcrumed on said 40 bracket, in coöperative relation with said box and cam; said bracket being thus arranged to coöperatively connect the stylus restoring mechanism with said stop device and means arranged to coöperate with said 45 terminal stop device; whereby movement of the latter, caused by movement of said box toward its terminal position, causes said driving mechanism to operate to return said arm and box to their initial position.
- 50 8. In a sound reproducing machine; the combination with a motor arranged to turn a sound record table; of an arm carrying a sound box arranged to coöperate with a sound record on said table; an initial stop 55 device, limiting the initial position of said arm at the outer limit of its movement with respect to the axis of said table; a terminal stop device carried with said box, limiting the terminal position of said arm at the 60 inner limit of its movement toward the axis of said table; means arranged to raise said box from its terminal position, shift it away from the axis of the table, and lower it to its initial position, including a cam; driving 65 mechanism for said cam, including a driving gear connected with said motor, a driven gear connected with said cam, and means including a single spring arranged to alternately connect and disconnect said gears; and means arranged to coöperate with said 70 terminal stop device; whereby movement of the latter, caused by movement of said box toward its terminal position, causes said driving mechanism to operate to return said arm and box to their initial position. 75
9. In a sound reproducing machine; the combination with a motor arranged to turn a sound record table; of an arm carrying a sound box arranged to coöperate with a sound record on said table; an initial stop device, limiting the initial position of said arm at the outer limit of its movement with respect to the axis of said table; a terminal stop member, carried by said arm, limiting the terminal position of said arm at the 80 inner limit of its movement toward the axis of said table; means arranged to raise said box and arm from said terminal position, shift them away from the axis of said table, and lower them to their initial position, including a cam revoluble on a horizontal axis; driving mechanism for said cam; means arranged to operatively connect said motor and driving mechanism, a driving gear connected with said motor, a driven 85 gear connected with said cam, and means including a single spring arranged to alternately connect and disconnect said gears; a 90 detent device normally preventing rotation of said cam, including a tappet connected with one end of said spring, and a tripping lever arranged to hold said tappet with said spring set to disengage said gears, but arranged to be encountered by said terminal stop member, whereby movement of the latter, caused by movement of said arm toward its terminal position, permits said driving mechanism to operate to return said box to its initial position. 95
10. In a sound reproducing machine; the combination with a motor arranged to turn a sound record table; of an arm carrying a sound box arranged to coöperate with a sound record on said table; a terminal stop device carried with said box, including a 100 gear rack stop member, a gear engaging said rack, and means on said gear whereby it may be manually turned to set said rack in different positions; limiting the movement of said box toward the axis of said table; stylus restoring mechanism including a rotary cam; driving mechanism for said cam; means arranged to operatively connect said driving mechanism with said motor; and a detent for said driving mechanism, normally preventing rotation of said cam, but arranged to be encountered by said 105 terminal stop member, whereby movement of the latter, caused by movement of said box toward its terminal position, releases 110

said detent and permits said driving mechanism to restore the stylus to its initial position.

11. In a sound reproducing machine; the combination with a motor arranged to turn a sound record table; of an arm carrying a sound box arranged to coöperate with a sound record on said table; an initial stop device, limiting the initial position of said arm at the outer limit of its movement with respect to the axis of said table; a terminal stop member, carried by said arm, including a manually operative gear and gear rack slide bar, limiting the movement of said arm toward the axis of said table; means arranged to raise said box from its terminal position, shift it away from the axis of said table, and lower it to its initial position, including a rotary cam; driving mechanism for said cam; and means arranged to coöperate with said terminal stop device; whereby movement of the latter, caused by movement of said box toward the axis of said table, causes said driving mechanism to operate to return said box to its initial position.

12. In a sound reproducing machine; the combination with a motor arranged to turn a sound record table; of an arm carrying a sound box arranged to coöperate with a sound record on said table; a terminal stop member, carried with said box, including a manually movable slide bar, limiting the movement of said box toward the axis of said table, and a spring arranged to hold said slide bar in the position to which it is manually adjusted with respect to said box, means arranged to raise said box from its terminal position, shift it away from the axis of said table, and lower it to its initial position, including a rotary cam; driving mechanism for said cam; and means arranged to coöperate with said terminal stop device; whereby movement of the latter, caused by movement of said box toward the axis of said table, causes said driving mechanism to operate to return said box to its initial position.

13. In a talking machine; the combination with means to turn a sound record; of a sound box having means to coöperatively traverse such a record; feed mechanism arranged to automatically return said box from its terminal position to its initial position, including a driving gear, and a shaft carrying a gear adapted to be engaged and disengaged with respect to said driving gear, by axial movement of said shaft, and a spring arranged to shift said shaft alternately in opposite directions; said spring being operatively connected with said shaft at one end, by a lever engaged with a grooved sleeve on said shaft, and having its opposite end operatively connected with a slide bar; a cam carried by said shaft

arranged to slide said bar to stretch said spring to disengage said gears; a lever detent arranged to normally detain said bar in the position in which it is set by said cam; and means, operative by the movement of said sound box toward its terminal position, arranged to release said detent; whereby such movement of said box effects the engagement of said gears to actuate said feed mechanism.

14. In a talking machine; the combination with means to turn a sound record; of a sound box having means to coöperatively traverse such a record; feed mechanism arranged to automatically return said box from its terminal position to its initial position, including a driving gear, and a shaft carrying a gear adapted to be engaged and disengaged with respect to said driving gear, by axial movement of said shaft, and a spring arranged to shift said shaft alternately in opposite directions; said spring being operatively connected with said shaft at one end, and having its opposite end operatively connected with a slide bar; a cam carried by said shaft arranged to slide said bar to stretch said spring to disengage said gears; a detent arranged to normally detain said bar in the position in which it is set by said cam; and means, operative by the movement of said sound box toward its terminal position, arranged to release said detent; whereby such movement of said box effects the engagement of said gears to actuate said feed mechanism.

15. In a sound reproducing machine; the combination with an arm carrying a sound box; of a stop device limiting the movement of said arm; including a slide bar carried by said arm, and means arranged to manually set said slide bar in different positions, including a gear carried by said arm and operatively connected with said bar; and spring actuated means arranged to prevent accidental displacement of said slide bar.

16. In a sound reproducing machine; the combination with an arm carrying a sound box; of a stop device limiting the movement of said arm; including a slide bar carried by said arm, and means arranged to manually set said slide bar in different positions, including a gear carried by said arm and operatively connected with said bar.

17. In a sound reproducing machine; the combination with a motor arranged to turn a sound record; of a sound box arranged to coöperate with such a record; and means arranged to feed said sound box, including a driving gear connected with said motor, a driven gear movable to and from engagement with said driving gear, a single spring associated with means whereby it may be alternately set to disengage said gears; means arranged to set said spring, includ-

ing a cam carried with said driven gear; means arranged to release said spring from the position in which it is set by said cam, including a tripping lever; and means carried with said box arranged to trip said lever when said box has been moved to a predetermined position by the operation of said motor.

18. In a sound reproducing machine; the combination with a sound box; of means arranged to carry said box and support it in different positions, including a pivoted arm, a bracket rigidly connected with said arm, and having a member arranged to stop the operative movement of said box, and a fulcrum member arranged to support a lever; and a lever fulcrumed on the last named support arranged to tilt said sound box to idle position, when actuated by stylus restoring means; and stylus restoring means,

coöperative with said lever, arranged to return said box to an operative position from the position in which it is stopped by said bracket member.

19. An article of manufacture, consisting of a bracket having a member adapted to be connected with the tone arm of a sound reproducing machine, and having a member arranged to support a sound box in idle position, a member arranged to stop the operative movement of said box, and a fulcrum member arranged to support a lever.

In testimony whereof, I have hereunto signed my name at Philadelphia, Pennsylvania, this 14th day of March, 1918.

EDWARD A. ESCHINGER.
